PACKAGING MACHINE

Francis B. Casey, Belmont, Mass., assignor to
 Dewey and Almy Chemical Company, North
 Cambridge, Mass., a corporation of Massachu-
 setts

Application July 24, 1940, Serial No. 347,205

3 Claims. (Cl. 226—47)

This invention relates to automatic lifting apparatus and particularly to a mechanism capable of lifting the heavier articles such as hams, turkeys and roasts from the expansion chamber of vacuum packaging apparatus. In a process commercialized under the trade name Cry O Vac, an elastic, expansible bag is placed over the open end of a vacuum chamber and the air pressure is rapidly lowered in the space between the walls of the chamber and the bag. Being elastic, the bag expands until it is forced into tight contact with the entire interior surface of the chamber. At this point, a dressed turkey, ham, or roast is inserted in the lined chamber, and a valve in the air exhausting pipe is closed. The mouth of the bag is then snapped off from the rim of the chamber and the bag and contents lifted out of the chamber. Then an evacuating nozzle is thrust into the open mouth of the bag which is then gathered by the hand of the operator and tightly held about the nozzle. Air is then pumped out from between the turkey, etc. and its elastic envelope. Subsequently, the bag is hermetically sealed and the turkey sent to the freezer and cold storage.

Although an operator may work all day on chickens and broilers without undue fatigue, it is quite otherwise when turkeys, hams, and roasts are handled, for the full weight must be lifted by the operator two feet or more with each packaging operation and held suspended while the bag is evacuated.

It is an object of this invention to expedite the packaging technique above described and to produce a lift which will raise the turkey out of the expansion chamber automatically at a predetermined time.

In the drawing

Fig. 1 is a side view of a turkey packaging machine showing in dotted outline the expansion chamber and the vacuum pump in their respective positions behind the side panel. It also shows in dotted outline a packaged turkey and the piston and evacuating nozzle in a semi-lifted position.

Fig. 2 is a longitudinal section through the lifting apparatus.

In carrying out my invention I supply a bracket 10 which supports the lift cylinder 11 centrally over the expansion chamber 12 of the apparatus. Inside the cylinder 11 I provide a piston 13 carried on a hollow piston rod 14, the open end of which carries the flared evacuating nozzle 15. Preferably the nozzle bears a perforated dia-

phragm 30 which prevents loose bits of meat from being sucked into the apparatus. The cylinder 11 is provided with heads 16 and 17. The upper head 16 bears a pipe connection 18 which leads through the pipe 19 to a two-way valve 21, while the lower head 17 carries a piston guide 22, and is provided with air ports 23 and 24.

In operation, the operator snaps the expansible bag 25 over the open end of the expansion chamber 12 and steps on the treadle 26 which is connected through linkage 27 to the valve 21. The pump 28 then exhausts the air in the expansion chamber 12 through the pipe connection 29. When the bag lines the wall of the chamber a turkey, for example, is inserted in the bag. Then the operator removes his foot from the treadle and spring 31 pulls the two-way valve into its alternative position where the pump 28 is connected to the pipe 19.

It is possible to allow the piston to fit so freely that the rod and evacuating nozzle will fall of their own weight, but many operators prefer to have the nozzle out of the way until wanted. In such a case, the piston leathers are fitted so tightly that the rod cannot fall, but

25 must be pulled downwards.

The neck of the bag which has been removed from the rim of the chamber is then gathered about the evacuating nozzle 15. At first, air in the bag is sucked out and then, as the bag hugs the turkey tightly, air entering through the ports 23 and 24 forces the piston upward, lifting the bag and turkey together. Spinning the turkey after it is lifted free of the container forms a twisted seal in the neck of the bag which may be permanently heat sealed, if the bag material permits, or securely tied in any manner.

I claim:

1. In food packaging apparatus, an expansion chamber, vacuum operated means for lifting a package from the chamber, said means including a retractible evacuating nozzle centrally positioned over the chamber, means for removing air from the chamber and said means for expanding and evacuating a package respectively, conduits connecting the air removing means to the chamber and to said vacuum operated means, and means rendering the chamber and the vacuum operated means alternately operative.

2. Packaging apparatus comprising an open ended expansion chamber, vacuum operated means for lifting a package from the chamber including a retractible evacuating nozzle positioned over the open end of the chamber, means associated with said nozzle and operative upon 50 shutting off of air to said nozzle to retract the

nozzle and lift a package from the chamber, and common means for withdrawing air from the chamber and said vacuum-operated means.

3. Apparatus for packaging material in flexible expansible containers comprising an open ended chamber for expanding the containers, vacuum operated means for evacuating a container and lifting it from the chamber including a cylinder, a piston, an evacuating nozzle, and a hollow piston rod arranged to permit air to

5 pass from the nozzle to the head space in the cylinder above said piston, air passages leading into the cylinder below the piston, and common means for withdrawing air from the chamber and said vacuum-operated means whereby upon the application of suction to the head space of said cylinder and upon the shutting off of the air supply to said evacuating nozzle, the piston will be raised by atmospheric pressure.

FRANCIS B. CASEY.
